UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed September 15, 1926, Serial No. 135,582. Renewed May 16, 1930.

This invention relates to firearms, and particularly to interlocking devices for various elements of the fire control mechanism. For the purpose of illustration, I have shown my invention as applied to a firearm of the type disclosed in U. S. Patent 1,143,170, June 15, 1915, to J. M. Browning, but it is to be understood that the invention is of general application and not limited to the particular gun illustrated.

In guns of the type disclosed in the Browning patent, shells or cartridges are stored in a tubular magazine extending longitudinally beneath the barrel, and are transferred one at a time to the chamber, and the shell in the chamber is fired by the impact therewith of a firing pin driven forward by a blow from a pivoted hammer, which is held in cocked position by the engagement with a notch therein of the nose of a sear integral with the trigger.

When the gun has been fired the functions of unlocking and retracting the breech block, ejecting the empty shell, cocking the hammer, transferring a fresh shell from the magazine to the chamber, and advancing and locking the breech block, are all performed by reciprocating an action bar attached to the forearm, the movement of the action bar and forearm being first rearward, then forward to initial position. Since guns of this type are fired from the shoulder, and are usually held against the shoulder by means of the forearm, it is necessary that the action bar be locked against rearward movement when the gun is in ready-to-fire condition. To this end the Browning patent above identified provides an action bar lock, and a control device therefor, associated with the hammer, which prevents retraction of the action bar while the hammer is cocked, unless the lock is released by manipulation of an extending finger piece.

It is likewise desirable that means be provided for preventing the fall of the hammer until the action bar has been fully advanced, thereby closing the breech and locking the breech block. The hammer is concealed in the receiver, and in order to cock the hammer it is necessary to fully operate the action. If the hammer can be moved forward as the

action is closed by holding the trigger depressed or by other manipulation, the hammer can be cocked only by again operating the action and thereby ejecting the unfired shell in the chamber.

Moreover, if the hammer can be released to move forward when the breech block is not closed and locked, there is danger that a shell or cartridge may be fired with the breech block in this condition, with serious injury to the mechanism or the shooter, or both. This is a contingency which must be carefully guarded against.

In the Browning patent above identified a device associated with the action bar lock engages the hammer and holds it in cocked position during the greater part of the forward movement of the breech block. However, the construction of this device is such that the hammer is released before the breech block is locked. Moreover, it is effective only if the action bar has been fully retracted. Assume that a fresh shell has been placed in the chamber and the breech closed and locked by one complete operation of the action bar. If the action bar lock is now withdrawn by manipulation of the finger piece provided for this purpose, and the action bar partially retracted, the hammer is then free from the locking device, and may be released in any position of the breech block by merely pressing the trigger. The action may then be closed with the hammer not cocked.

It is an object of the present invention to provide a fire control mechanism which positively insures the engagement of the hammer by the hammer retaining devices whenever the hammer is cocked and, likewise, positively secures said retaining devices in engagement with the hammer at all times when the breech mechanism is unlocked, regardless of the manipulation by which the breech becomes unlocked.

It is, furthermore, an incidental object of the invention to provide hammer engaging devices which are retained in ineffective position while the hammer is displaced from cocked position and are positively moved to engage the hammer whenever the hammer reaches cocked position.

With these and other objects in view the invention consists in the novel combinations and arrangements of parts which are illustrated in the drawings and will be herein-
5 after described.

In the drawings:

Fig. 1 is a fragmentary side elevation, partly in section, of the receiver of a gun embodying the present invention. As shown
10 in this figure, the action is closed and locked and the hammer is cocked.

Fig. 2 is a fragmentary sectional elevation, showing the parts in the position which they assume during the opening of the breech,
15 after the gun has been fired. Many parts are omitted from this figure for the sake of clear-
ness.

Fig. 3 is a view similar to Fig. 2, showing the parts in the position they assume when
20 the action bar is fully retracted.

Fig. 4 is a similar view, showing the position of the mechanism of the present invention when the hammer is cocked and the action bar unlocked, or unlocked and partly
25 retracted.

Fig. 5 is a plan view of the trigger plate and parts mounted thereon.

The fire control mechanism is housed in a receiver or frame 10 having a bottom opening 11, thru which the fresh shells are inserted into the magazine 12 and the empty shell cases are ejected. Slidably mounted in the sides of the frame is an action bar slide 14, adapted for connection by means of pin
30 15 to an action bar associated with the usual forearm (not shown). The action bar slide 14 is thus adapted to be reciprocated by manipulation of the forearm, and the reciprocation of the action bar controls the operations
35 incident to ejecting the empty shell case from the chamber and feeding the fresh shell from the magazine to the chamber in the manner which will be hereinafter described. The breech block, indicated generally by 17, com-
40 prises longitudinal recesses which contain the extractor 18 and the firing pin 19. The firing pin is held in place by cross pin 20 and is re-
50 tracted from engagement with the head of the shell by spring 21. A recess cut in the top of the frame 10 forms a recoil shoulder
55 22 adapted to engage the end 23 of the breech block, thereby locking the breech block in breech closing position until it is lowered by movement of the action bar.

55 A lug or hook 24 projecting downwardly from the breech block is adapted to engage a recess 25 in the action bar slide 14 as clearly shown in Fig. 2. When the action bar is drawn rearwardly the forward edge of hook
60 24 is engaged by an inclined cam face 26 on the action bar slide whereby the breech block is lowered out of engagement with recoil shoulder 22. Further rearward movement of the action bar draws the breech block
65 rearwardly, breech block and the action bar

slide moving together. On the forward movement of the action bar, the action bar slide and breech block move together until the breech is closed and the end 23 of the breech block is in front of recoil shoulder
70 22. As the forward movement of the action bar is completed the inclined cam face 27 of action bar slide 14 raises the breech block into engagement with recoil shoulder 22.

The means for retaining shells in the magazine, and for releasing them one at a time to be transferred to the chamber comprises a retainer 28, normally in engagement with the head of the rearmost shell in the magazine, but adapted to be withdrawn and release the rearmost shell near the end of the rearward movement of the action bar slide. A cartridge stop lever 29 is adapted to be rocked about its horizontal pivot into position to engage the head of the second shell in
80 the magazine and hold this shell until the retainer 28 is restored to effective position.

The means for transferring the shell released from the shell retaining devices to position to be moved into the chamber by the head of the breech block, comprises a carrier device, pivoted at 30 to the sides of the frame
90 10. This carrier device comprises longitudinally extending spring fingers 31 connected at their rear ends by a cross piece 32. When the breech is closed the carrier fingers are in the position indicated in Fig. 1. As the action bar and breech block begin to move rearwardly, the ends of fingers 31 engage cams
95 33 on the sides of the breech block, moving the fingers upwardly into a recess 34 in the top of the receiver. In the further rearward movement of the breech block, the empty shell is withdrawn from the chamber beneath the carrier fingers. As the breech block and action bar slide reach the end of their rearward movement, cross piece 32 is engaged by cam face 36 at the rear of the action bar slide and the carrier fingers are quickly moved downwardly to eject the empty shell cases, and to receive a fresh shell from the magazine. As the action bar slide reaches the end of its rearward movement the rearmost shell in the magazine is released from retainer 28 and is pushed out of the magazine on to the carrier fingers 31 by the magazine spring. As the action bar slide begins to move forward, inclines 37 on the carrier fingers are engaged by cam faces 38 on the action bar slide, and the carrier fingers, with the shell which has been placed thereon, are elevated to the position shown in Fig. 1. As the breech block moves forward, the shell is pushed into the chamber by the breech block, the carrier fingers being spread to permit the passage of the breech block, and dropping behind the cam shoulders 33. The shell retaining and transferring devices are more fully described in the Browning patent
110 above identified.

At the rear of the cartridge or shell opening 11 is a trigger plate 40, which carries certain elements of the fire control mechanism, including a hammer 41. The hammer is pivoted on a transverse pin 42, and is connected by means of a pin 43 with a rearwardly extending hammer link 44. A hammer spring 45 lies in a suitable recess in the trigger plate, and a spring follower 46 engages the end of hammer link 44.

A trigger 47 pivoted in the trigger plate 40 at 48 comprises a forward extension or nose 49 adapted to rest against the back of the hammer 41 adjacent to a shoulder 50 thereon, when the hammer is in cocked position. Forward from the shoulder 50 the peripheral surface 51 of the hammer is concentric with the pivot 42. Whenever the hammer is displaced from cocked position the engagement of nose 49 with surface 51 holds the trigger and associated parts in hammer releasing position. A manually actuated trigger controlling "safety" stud 471, mounted in the trigger plate for transverse sliding movement between "safe" and "firm" positions, cooperates with a ledge 472 which extends upwardly and rearwardly from the trigger. In one position of the stud 471 the ledge 472 engages the side of the stud and movement of the trigger is blocked. In the other position of stud 471 ledge 472 may enter a notch 473 in the stud, hence the trigger may be moved. The trigger is pressed into engagement with a pivoted L shaped sear 52 by means of a light spring 521 interposed between the trigger and the trigger plate and occupying a recess in the trigger. The sear 52, which is pivoted at 53, comprises two downwardly extending projections 54 and 55 on opposite sides of the pivot 53. The forward projection 54 is normally in engagement with the trigger, while the rear projection 55 is spaced from the trigger. Thus there is effected a positive means for limiting the movement of the sear within its operative range. The upwardly extending part of the sear comprises a nose 56 adapted to engage a notch 57 on the hammer. The sear further comprises a lateral projection 58, for a purpose which will be presently explained. The sear is pressed into engagement with the hammer and the trigger is held in the position shown in Fig. 1 by means of a spring 59 encircling a plunger 60 pivoted at 61 in the trigger plate and extending into a recess in the sear. Spring 521 is light in comparison with spring 59, so that the sear and trigger are normally held in the position shown in Fig. 1, spring 521 being compressed. The forwardly extending toe of the sear comprises a projection 62 adapted to be engaged by the back of the hammer as the hammer is moved slightly past cocked position by the action bar slide (Fig. 3), this engagement serving to positively move the sear into ham-

mer engaging position. An action bar locking member 63 pivotally mounted in the trigger plate on the pin 48 is urged to action bar locking position by a spring 65 partly contained in a recess in the trigger plate. Said member 63 comprises a forwardly extending nose 66 adapted to engage the heel 67 of the action bar slide 14, when the action bar is fully forward and the breech locked, as shown in Fig. 1.

For the purpose of rocking the action bar lock 63 to release the action bar slide when the hammer moves forward, a stiff spring wire 68 is secured in the forward part of the action bar lock, passes beneath a stud 69 thereon and at its rear end 70 extends transversely over the hammer link 44. The hammer link comprises a cam surface 71 which engages the lateral extension 70 of spring 68, as the hammer and hammer link move forward. When hammer is cocked spring 68 is under no tension, spring 65 holding the action bar lock in effective position, as heretofore stated. However, when the transverse extension 70 of the spring engages the cam 71 the spring 68 is stressed sufficiently to overcome the force of the spring 65 and tends to rock the action bar lock to ineffective position.

The present invention further contemplates the provision of a locking device capable of positively blocking the hammer releasing movement of the sear, whenever the action bar lock is ineffective. To this end a sear blocking member 72 is pivoted in the trigger plate on the pin 61 in position to move behind the lateral projection 58 of the sear. The blocking member 72 is controlled by a spring member 73 somewhat similar to the spring 68. Said spring 73 is secured to the action bar lock at its forward end, adjacent to spring 68 and, like spring 68, passes under the stud 69. The end of spring 73 is received in a stud 74, rotatably mounted in the sear blocking member 72. When the action bar lock is in its effective (Fig. 1) position spring 73 tends to rock the sear blocking member downward to ineffective position. When, however, the action bar lock is rendered ineffective, either by the forward movement of the hammer or by manual depression of the extending finger piece 75 of the action bar lock, the stress in spring 73 is reversed, so that it tends to move the blocking member 72 into sear movement blocking (Fig. 4) position.

When the action bar slide 14 is fully retracted (Fig. 3) it lies partly to the side and entirely clear of the action bar lock 63. It is necessary therefore, to provide other means to hold the nose of the action bar lock depressed, and thereby prevent the possibility of the release of the hammer from the sear while the action is open. For this purpose a lug 76, fixed to the side of the hammer, co-

operates with a shoulder 77 on the action bar lock. The hammer being at this time held retracted by engagement with the lower face of the action bar slide the action bar lock is held with the nose 66 depressed, and the parts controlled by the action bar lock are positioned accordingly.

The operation of the improved fire control mechanism is as follows:

When the gun is ready to fire the parts are in the position shown in Fig. 1. The breech is closed and locked by the engagement of foot 24 on the breech block with part 27 on the action bar slide. The hammer is held in cocked position by the engagement of sear nose 56 with hammer notch 57. The nose 49 of the trigger rests against the back of the hammer near the shoulder 50. The sear and trigger are held in this position by spring 59, the light spring 521 holding the trigger up against the sear. The ledge 472 is clear of the notch 473, thus the stud 472 may be moved to trigger blocking position if so desired. The action bar lock is effective, being so held by spring 65. Spring 68 is neutral and spring 73 is so tensioned as to draw the sear blocking member 72 downward to its ineffective position. The safety stud being positioned with notch 473 opposite ledge 472, the trigger may now be depressed, simultaneously withdrawing sear nose 56 from notch 57 and trigger nose 49 out of the path of the shoulder 50. The hammer moves forward impelled by spring 45. As soon as the hammer is displaced the sear and trigger are locked in their retracted positions by the engagement of trigger nose 49 with the locking surface 51 concentric with the hammer pivot. The safety stud 471 is also locked, ledge 472 occupying notch 473. As the hammer reaches its forward position and the cartridge in the chamber is fired the action bar lock is rotated about its pivot by the engagement of the transverse extension 70 of spring 63 with the cam surface 71 on the hammer spring rod. The action bar is thus unlocked and simultaneously spring 73 is stressed so that it tends to move the sear blocking lug 72 to effective position behind the lateral projection 58 of the sear. The sear, however, is at this time held in retracted position, as heretofore explained, so that the blocking lug 72 merely moves into engagement with the under side of the lug 58, spring 73 remaining under tension and tending to move the blocking lug upward.

The gun being fired the action bar may now be retracted and on this movement the hammer is cocked by engagement with the lower face of the action bar slide 14. The relation of these parts is such that the hammer is moved slightly past full cocked position and, the back of the hammer engaging the projection 62 on the toe of the sear, sear and trigger are positively moved to hammer hold-

ing positions. This movement of the trigger is permitted as soon as the hammer reaches full cocked position, the shoulder 50 having passed from beneath the trigger nose 49, which is thereupon permitted to move upward. As an incident to the movement of the trigger, ledge 472 is withdrawn from notch 473, freeing stud 471 for movement at will to "safe" position. As the sear moves forward to hammer engaging position this lateral projection 58 rides off from the blocking lug 72, which lug is now moved by spring 73 behind the sear projection 58, thus locking the sear in hammer holding position. The blocking lug 72 remains in this position (Fig. 4) until the action is fully closed and the action bar lock rocked to its Fig. 1 position. The latter movement reverses the stress in spring 73 and the sear blocking lug is thereupon restored to its ineffective (Fig. 3) position.

If the finger piece 75 is now manipulated to release the action bar, the member 72 is at once raised to sear blocking position, and so remains until the action bar is again locked. It should be noted that member 73 is substantially rigid, but is sufficiently flexible to be deflected to the Fig. 2 position while the hammer is displaced, and sufficiently elastic to be restored to normal when the hammer is cocked and the sear engaged with the hammer.

Variations in the structure illustrated and described, as well as in the construction of the firearm to which it is applied may be made, it being understood that the embodiment of the invention herein shown is illustrative rather than restrictive, the invention being limited only by a broad interpretation of the appended claims.

What is claimed is:

1. In a firearm, a firing hammer, a holding sear therefor, a sear controlling trigger adapted to be moved to cause the sear to release the hammer, and means associated with said trigger and engaging said hammer, adapted to prevent the restoration of the sear to hammer engaging position while the hammer is displaced from cocked position.

2. In a firearm, a firing hammer, a trigger, a pivoted hammer engaging sear having projections on the opposite sides of its pivot adapted to engage the trigger, a nose on the trigger, and a locking surface on the hammer adapted to engage the nose when the hammer is out of cocked position, whereby the sear and the trigger are locked against movement to hammer engaging position when the hammer is displaced from cocked position.

3. In a firearm, a firing hammer, movable from cocked position to fired position, a trigger, a hammer engaging sear controlled by said trigger, a device for locking said sear in engagement with said hammer, means tending to move said device to locking position rendered effective when said hammer is moved

to fired position, and means for preventing movement of said device to locking position until said hammer is returned to cocked position.

4. In a firearm, a firing mechanism, a trigger, a trigger controlled sear, an action bar, an action bar lock controlled by said hammer, and a sear lock controlled jointly by said action bar lock and said hammer; whereby said sear is locked in hammer engaging position whenever the hammer is cocked and the action bar lock is ineffective, and is locked in retracted position whenever the hammer is displaced from cocked position.

5. In a firearm in combination, a pivoted firing hammer, a pivoted sear adapted to engage and hold said hammer, a trigger, a plurality of projections on said sear adapted to engage said trigger, a surface on said hammer concentric with its pivot, a notch in said hammer adjacent said concentric surface, a nose on said trigger adapted to engage said notch when said hammer is in cocked position and said concentric surface when said hammer is displaced from cocked position.

6. In a firearm, a hammer, a trigger, a sear adapted to engage said hammer, a plurality of spaced devices associated with said sear adapted to engage said trigger, whereby depression of said trigger is effective to first move said sear to hammer releasing position, then to positively arrest its movement.

7. In a firearm in combination, a firing mechanism movable from cocked position to fired position, a firing mechanism engaging sear, a sear actuating trigger, an action bar, a bar lock movable from effective to ineffective position, means for positively holding said sear in hammer releasing position during the displacement of said firing mechanism from cocked position, and means for positively locking said sear in hammer engaging position when said hammer is cocked and said action bar lock is in ineffective position.

8. In a firearm, in combination, a breech mechanism operating member, a lock therefor, a hammer, a hammer engaging sear, a trigger plate, a sear controlling trigger mounted in said trigger plate, said sear being a separate member from said trigger, and means for preventing the hammer disengaging movement of said sear, pivoted in said trigger plate and controlled by said lock.

9. In a firearm, in combination, a hammer, a hammer engaging sear, movable to disengage the hammer, a trigger plate, a sear controlling trigger pivoted in said trigger plate, and means for preventing the hammer disengaging movement of said sear pivoted in said trigger plate, a spring pressing said sear into hammer engaging position, and carried by a stud pivoted in said trigger plate adjacent said means.

10. In a firearm, in combination, a hammer,

a trigger provided with a forwardly extending nose adapted to engage said hammer, and a separate hammer controlling sear actuated by said trigger.

CRAWFORD C. LOOMIS.
